UNITED STATES PATENT OFFICE.

HENRY G. CORDLEY, OF GLEN RIDGE, NEW JERSEY.

DISPENSING-STAND.

1,207,278.

Specification of Letters Patent. Patented Dec. 5, 1916.

Application filed January 14, 1915. Serial No. 3,150.

To all whom it may concern:

Be it known that I, HENRY G. CORDLEY, a citizen of the United States, residing at Glen Ridge, in the county of Essex, State of New Jersey, have invented certain new and useful Improvements in Dispensing-Stands, of which the following is a description, reference being had to the accompanying drawings, forming a part hereof.

10 The invention relates to dispensing stands for dispensing liquids for use as beverages or for other purposes and has for its object to provide a simple, strong and efficient stand adapted for dispensing liquids from the original bottles or other containers and cooling the liquid so that it will be dispensed at a temperature suitable for drinking.

With these objects in view, the invention consists in the construction and combination of elements hereinafter described and claimed.

Referring to the drawings, Figure 1 is a central vertical sectional view of a dispensing stand embodying the invention. Fig. 2 is a horizontal sectional view on line 2—2, of Fig. 1, Fig. 3 is a horizontal sectional view on line 3—3, of Fig. 1, and Fig. 4 is a central vertical sectional view similar to Fig. 1 but showing a modified construction.

30 In the drawings, 1 indicates a bowl having a flat bottom 2 and having its side walls flaring outward toward their upper edge, as indicated at 3. At opposite points on the upper edge of the bowl are secured upwardly extending arms 4 which are curved inward so that their upper ends are a distance apart slightly greater than the diameter of a bottle 5. To the upper ends of these arms is secured a horizontal strip 6 bent into the shape of a ring adapted to fit around the body of the bottle 5 and having its ends slightly separated.

To the under side of the bottom 2 of the bowl are secured the inwardly bent upper ends 6 of strips 8 which extend downward and outward to form supporting legs and have their lower ends bent inward to form feet 9. These legs which are preferably four in number are braced by a ring 10 secured to them near their upper ends and also by a ring 10' secured to them about midway of their length.

Through the center of the bottom 2 of the bowl extends a hollow plug 11 having formed thereon a shoulder 12 adapted to rest against the under surface of the bottom

and having a lock nut 13 fitting on a screw-threaded portion of the plug resting against the upper surface of the bottom 2 and clamping the bottom firmly between it and the shoulder 12. Above the lock nut, the hollow plug is adapted to fit into the mouth of the bottle and is provided with a packing 14 of cork or other suitable material to make a liquid tight joint. The plug 11 has two passages through it, passage 15 for the outflow of liquid and passage 16 for the inflow of air. To the upper end of the inflow passage is secured an air inlet tube 17 of such length as to reach nearly to the bottom of the inverted bottle.

Below the shoulder 12 the plug is provided on one side with a recess 18 to receive the end of a horizontal tube 19, the outer end of which is provided with an enlargement 20 to receive the inner end of a push faucet 21 having a valve seat 22 to receive a valve 23 carried by a valve rod 24 having at its outer end a push button 25 against which a spring 26 acts to hold the valve to its seat, the faucet having a discharge nozzle 27. The tube 19 is in communication at its inner end with liquid outflow passage 15 of the hollow plug.

On its side opposite to the recess 18, the plug is provided with a rearward extension 28 having formed therein a horizontal passage 29 open at its outer end and in communication at its inner end with the air inflow passage 16. Below passage 29 and in line with the valve rod of the faucet, a recess 30 is formed in the extension 28 adapted to receive a packing 31 through which passes a rod 32 connected at its inner end to the valve rod 24 in rear of the valve 23 and provided at its rear end with an arm 33 secured to it by a pin 34 and extending up in line with the open end of passage 29, the arrangement being such that when the push button is pressed inward to unseat the valve 23, the rod 32 will move the arm 33 away from the open end of the passage 29 so as to permit air to enter as the liquid is drawn off.

105 Suitable packing may be used if necessary to insure a tight joint between the plug 11 and the bottom of the bowl 1.

In use, the cork is drawn from the bottle containing the liquid to be dispensed and the stand is then inverted over it and the end of plug 11 fitted into the bottle neck. The stand is then returned to upright po-

sition, the bottle being inverted. Crushed or broken ice is then placed in the bowl about the bottle neck. The contents of the bottle are then drawn off as wanted by pressing the push button of the faucet, which opens the passage for the liquid and at the same time by movement of the arm 33 opens the air inlet passage to permit the liquid to flow from the bottle.

10 The above may be readily formed from sheet metal by stamping or otherwise and the supporting legs, the upper arms and the rings may all be readily formed from flat strips of metal of suitable width secured 15 together and to the bowl by rivets.

In Fig. 4, I have shown a modified construction in which the air inlet passage 29 is not controlled by the arm 33 but has connected to its outer end a pipe or tube 20 35 which extends outward to or slightly beyond the edge of the bottom 2 of the bowl and thence upward, preferably outside the side of the bowl to or beyond the edge 3. In this construction, the air inlet tube 17 25 may be dispensed with, though it may be used as indicated in dotted lines if it is desired to avoid having the air bubble up through the contents of the bottle. The connection with the bottle may be by means of 30 a hollow plug, as shown in Fig. 1, or may be, as shown in Fig. 4, by means of a cup 36 into which the mouth of the bottle fits, this cup

having in its bottom, a disk 37 of cork or other relatively soft material against which the mouth of the bottle rests so as to make 35 a liquid tight joint.

In the construction shown in Fig. 4, there is, of course, no need for providing the faucet with any connection for controlling the air inlet as the air inlet pipe or tube 35 40 is always open.

Having thus described my invention, what I claim is:—

A dispensing stand for inverted bottles comprising a bowl adapted to contain ice, 45 having a flat bottom, a hollow plug extending upward through the bottom of the bowl, a draw off faucet connected to the hollow plug below the bottom of the bowl, supporting legs having their upper ends bent inward and secured to the bottom of the bowl, resilient arms extending upward from the upper edge of the bowl and a horizontal strip secured to the upper ends of said resilient arms, bent into the shape of a ring 50 55 and having its ends separated to inclose an inverted bottle extending into the bowl and into engagement with said hollow plug.

This specification signed and witnessed this ninth day of January, A. D. 1915.

HENRY G. CORDLEY.
